UNITED STATES PATENT OFFICE.

JULIUS R. BRUECKNER, OF DETROIT, MICHIGAN, ASSIGNOR TO GIBB INSTRUMENT COMPANY, OF DETROIT, MICHIGAN, A CORPORATION OF PENNSYLVANIA.

ALTERNATING-CURRENT TRANSFORMER.

Application filed August 23, 1920. Serial No. 405,466.

To all whom it may concern:

Be it known that I, JULIUS R. BRUECKNER, a citizen of the United States, residing at Detroit, county of Wayne, State of Michigan, have invented a certain new and useful Improvement in Alternating-Current Transformers; and declare the following to be a full, clear, and exact description of the same, such as will enable others skilled in the art to which it pertains to make and use the same, reference being had to the accompanying drawings, which form a part of this specification.

This invention relates to alternating current transformers for electric welding systems. Electric arc welding transformers have been devised heretofore and in such previous cases, for instance as shown in the U. S. Patent for Morton Arendt, No. 1,146,988 of July 20, 1915, an inductance or reactance coil is used in the secondary circuit or such circuit is provided with an interwoven or additional secondary winding as in the U. S. Patent to Claude J. Holslag No. 1,305,362 of June 3, 1919, or an auxiliary secondary coil is wound somewhere along the magnetic core which functions as a reactance or a choke coil.

All these former devices have a large ohmic resistance (since impedance may be looked upon in the same light as ohmic resistance) and these former types of transformers are therefore of low efficiency due to excessive consumption of power which is required to overcome the reactance coil inserted in the circuit.

In all these former cases and also in this present invention, the object is to secure a steady arc after once being struck and to prevent the arc from "blowing out" during the change in current from positive to negative through the zero value. In the ordinary standard type of alternating current transformer utilizing a current having a frequency of sixty cycles per second, the change in voltage from positive to negative is so slow that the gas formed at the arc (which is the current conducting element) has time to dissipate making such transformers unsuitable for arc welding.

The introduction of reactance coils and the like as heretofore mentioned results in a distortion of current flow to cause rapid drop in voltage through the zero value.

The curve of the instantaneous values during this continuous change from positive to negative is termed the current or E. M. F. wave form and for all practical purposes may be considered a sine wave which is usually peaked or rounded at the top. By introduction of reactance coils in the secondary circuit as heretofore mentioned, the wave form may be changed thus flattening out the top of the sine wave with a sudden change from maximum positive to maximum negative across the neutral points.

This distortion of the sine wave is a direct result of the difference in phase relation of the E. M. F. and current. If this distortion is caused by reactance the current lags behind the E. M. F. An object of this invention is to provide an alternating current electric arc welding transformer of very simple construction dispensing with or avoiding the use of reactance coils, or additional magnetic by-paths, interwoven or split secondaries and in which the current loss is reduced to a minimum. Further, the object is to provide a construction productive of a steady arc and an even stable flow of current across the arc and distinguishes from the former devices above mentioned in that the construction provides a definite means of producing a short and steady arc by magnetic flux distortion rather than by direct current distortion as in the former cases. In other words—the object of the invention is to provide a transformer having a core of such construction and design as to induce a current in the secondary in which the change through the neutral point from maximum positive to maximum negative value is sudden instead of producing a secondary current of substantially normal wave form and introducing an instrumentality in the circuit to distort such wave form as is the usual practice. With my invention a current of the desired character is primarily set up in the secondary. With all other devices of this character with which I am acquainted the induced current is acted upon to cause the sudden drop from maximum positive to maximum negative value. These and other

objects and the several novel features of the invention are hereinafter more fully described and claimed and the preferred form of construction of a transformer embody-

ing my invention is shown in the accompanying drawings in which—

Fig. 1 is a side elevation of a transformer.

Fig. 2 is a detail of the mechanism for moving the secondary coil.

Fig. 3 is a plan view of the transformer, taken on line 3—3 of Fig. 1.

Fig. 4 is a diagram showing the wave form of the standard type of transformer.

Fig. 5 is a diagram showing the ideal wave form of the secondary current as approximately produced by the transformer here shown.

My improved transformer is of the usual shell type having three legs, 1, 2 and 3. The primary coil 4 and the secondary coil 5 are two distinct units each surrounding the center core 2 and the primary winding is securely fastened at the lower end of the core 2. This fastening may be of any approved type as by bolts 6 passing through a frame 7 and base member 8 of the transformer. The secondary winding 5 is movable on the core 2 and by movement of the secondary coil the secondary current may be varied as heretofore described. When the secondary is nearest the primary the maximum secondary current is obtained and when furthest from the primary the minimum current is available. This movement of the secondary coil is accomplished by means of a rack 9 which extends upward through the closed casing of the transformer and engages a pinion 11 shown more particularly in Fig. 2 on the shaft of the operating wheel 10. This movable secondary is essential for different classes of work requiring a greater or less degree of heat at the arc. As the transformer is preferably enclosed within a casing 12 some means should be provided to enable the operator to determine the relative position of the secondary coil as for instance by placing graduation lines (not here shown) on the rack end 9.

The primary coil is provided with leads 13 and 14 while the secondary coil is provided with the leads 15 and 16 the lead 15 providing the ground line and the line 16 being provided with an electrode holder 17. These several leads are connected with the respective coils in the usual manner being supported on the upper end of the transformer by insulating block 18. The closed casing is filled with oil preferably to about the upper end of the transformer so that both coils are immersed in the oil. I have found by a series of carefully conducted experiments that, by maintaining the core portions in certain relation to the winding of the primary and secondary and the length of the core in definite proportion to the width of the windows of the transformer I am able to dispense with additional secondary windings or intermingling the pri-

mary and secondary or the addition of a reactance coil or the like in the secondary circuit. Therefore, by the construction stated the impedance or ohmic resistance of the windings is reduced to a minimum.

The relative proportions of the core parts that I have found most effective is in providing a "window" of three and one-half inches width and fifteen inches in length with a two inch width of each outside leg and four inch width of central leg. The capacity of transformers may be varied by adding metal to the side thereof to increase the cross sectional area and cubical content of the core parts.

This structure permits the use of a comparatively low voltage open circuit for the striking of the arc greatly reducing the shock hazard and providing a core of sufficient capacity to permit the magnetic flux to surge without leakage when the transformer is on open circuit.

The comparatively narrow windows also provide a ready means for magnetic leakage when the transformer is under load (that is when an arc is maintained).

By reducing the ohmic resistance to a minimum (as by elimination of choke coils etc.,) the current losses are reduced and at the same time a steady and an even flow of current across the arc is secured.

These beneficial results are obtained through distortion of magnetic flux rather than by directly distorting the current as formerly and the theory of operation is as follows: When the secondary circuit is open and current passing through the primary, the magnetic field is unobstructed throughout the several parts of the core.

Upon closing of the secondary circuit, as in the striking of the arc, and with the secondary spaced to some extent from the primary, there is what is termed a magnetic leakage between the central leg and outside legs of the core between the two coils, the extent of which is determined by the spacing of the coils.

When the secondary circuit is closed, the magnetic flux may not take its normal path due to the counteracting influence of that set up by the secondary coil at the upper end of the core.

The greater the distance between the secondary coil and the primary coil the less will be the amperage and the greater the voltage of the secondary current and decreasing the distance between the coils increases the amperage and decreases the voltage.

It is well known in the art that a short arc is essential in the production of a good weld and that, due to oxidation, the weld is brittle when a long arc is maintained.

With the construction of apparatus according to my invention the arc will extinguish upon lengthening to a dangerous point due to the comparatively low voltage of the secondary circuit and thus the length of the

arc possible to be drawn is automatically regulated and maintained within the necessary limits for the production of a good weld. For the usual arc welding operation, 5 the secondary coil should be positioned about midway between the primary coil and upper end of the core in the design herein described.

As above outlined the transformer is of 10 simple construction, there being but three units—namely, the shell type core, primary winding and secondary winding. All other devices for arc welding with which I am familiar have additional coils, additional 15 magnetic bi-paths, or interwoven or split secondary coils, etc., through or by means of which the desired distortion of the current wave form is secured and heretofore deemed necessary in securing the desired 20 wave form. By the particularity of construction and design of my transformer, especially the narrow windows having a width practically one-fourth of the height, a ready leakage of magnetic flux is permitted 25 when the coils are separated, and I avoid the detrimental features of the former construction mentioned and secure the following desired results—namely, low current consumption due to the current impedance 30 being reduced to a minimum, a comparatively low voltage on striking the arc and, simply varying the position of the secondary, automatically varies the extent of magnetic leakage and varies the character of the 35 current to correspondingly vary the heat developed at the arc.

The benefits obtained by the construction heretofore set forth results principally from the use of an excessive mass of iron 40 in relation to the mass of copper with a comparatively very short magnetic air gap secured by the narrow window construction. As before stated, the central leg of the transformer has a width equal to the two outside legs with the air space therebetween about one-fourth the height. The transformer is made of a series of plates so that the length of the transformer may be increased or diminished readily by addition 45 or removal of one or more plates. In the specific-transformer heretofore mentioned having "windows" of about three and one-half inches by fifteen inches I use approximately ninety-two turns in the primary 50 coil, using a flat wire .125 thick and .375 wide. The second coil is made of forty-four turns of two wires each of .125 by 1440. With the construction I secure ninety volts 55 in the secondary circuit with 220 volts in the primary circuit. The mass of iron weighs approximately 200 pounds, and the mass of copper weighs approximately 70 pounds. With this construction the voltage in the 60 secondary on open circuit is ninety irrespective of the position of the secondary.

There is no variation in the voltage that may be detected by any of the usual instruments whether the secondary is positioned adjacent the primary coil or at a point most remote therefrom. This indicates 70 positively that there is no magnetic leakage whatever when the secondary is on open circuit although, by reason of the short air gap a very ready magnetic leakage occurs on closed circuit as the magnetic flux of the primary is counteracted by that of the secondary. The essential characteristic of my invention consists in the provision of an excessive mass of iron relative to the copper 75 as compared with that of the standard alternating current type of transformer and in so constructing the transformer to permit a high degree of magnetic leakage to readily shorten the path of the magnetic circuit of the primary coil. In this manner, 80 when the secondary circuit is closed, as upon striking an arc, a distortion of the magnetic flux of the primary coil is occasioned and, as this is out of phase with that set up by the secondary on closed circuit, a prolongation of the maximum positive and maximum negative values of the secondary current is occasioned together with a sudden drop therebetween through the neutral point. This is a desired wave form of 85 secondary current as heretofore stated and by the construction described, a current of the desired wave form is primarily effected in the secondary circuit rather than secondarily effected through the introduction in 90 the secondary circuit of a reactance coil or the like as has been the practice. The specific proportions of the transformer parts herein specified are given solely as an example and it is to be understood various 95 changes may be within the limitations of the appended claims without departing from the spirit of the invention.

Having thus fully described my invention, what I claim and desire to secure by Letters Patent of the United States is—

1. An alternating current transformer for use in electric arc welding comprising a core formed with three legs of magnetic material connected together at the top and bottom, the "windows" between the legs being of a width substantially one fourth their length providing a short air gap, a primary circuit having a coil at the bottom of the central leg, a secondary circuit, a movable coil therein on the central leg above the primary coil, means for holding the secondary coil at any of its possible distances from the primary, the secondary coil and circuit being free from ohmic resistance other than that inherent in the wire forming the same and the resistance of the arc.

2. An alternating current transformer for use in electric arc welding comprising a laminated core formed of three legs of mag-

- netic material connected together at the top and bottom and having narrow "windows" between the legs providing a short magnetic air gap permitting ready magnetic leakage, 5 a primary circuit having a coil at the bottom of the central leg, the mass of iron being sufficient to permit surge of magnetic flux without leakage, a secondary circuit having a coil on the central leg adapted to be adjusted to various definite positions relative to the primary, the secondary coil and circuit being unimpeded except by the inherent resistance of the wire and the resistance of the arc. 10
- 15 3. An alternating current transformer for use in electric arc welding comprising a core formed of three legs of magnetic material connected together at the top and bottom, the width of the central leg being substantially equal to that of both the other legs and the three legs being connected together at the top and bottom, the "windows" between the legs being comparatively narrow and of the same width throughout their length and providing a comparatively short magnetic air gap permitting ready magnetic leakage, a primary circuit having a coil on the core, a secondary circuit also having a coil on the core, means whereby 20 one of the coils may be positioned and held, the flow of current through either of the circuits and respective coils being impeded only by the natural resistance of the wire forming said circuits and the resistance of the arc in the secondary circuit. 25
- 30 4. An alternating current for use in electric arc welding which comprises a core formed of three legs of magnetic material connected together at the top and between 35 and providing "windows" between the legs of a uniform width of about one-fourth their
- length providing a short magnetic air gap and whereby the extent of magnetic leakage is proportioned to a distance the coils are positioned apart, a primary circuit having a coil fixed at the bottom of the central leg, a secondary circuit free from impedance except that natural to the wire of the circuit and the resistance of the arc and having a coil about the central leg and movable thereon relative to the primary, and means for positioning the secondary and holding the same at various predetermined distances from the primary coil whereby the amperage of the secondary circuit is determinable. 45 50 55
5. An alternating current transformer for use in electric arc welding comprising a core having a cross sectional area sufficient to normally permit unrestricted magnetic flux, said core further having a form permitting a high degree of magnetic leakage, a primary coil and circuit therefor of a character permitting practically unimpeded flow of current, a secondary circuit free from impedance except that natural to the wire and the resistance of the arc and having a coil movable toward or from the primary coil to effect magnetic leakage by distorting the magnetic flux of the primary coil to a desired extent, the said secondary coil and circuit therefor, by reason of the freedom of magnetic leakage and unrestricted magnetic flux having current primarily induced therein of a wave form having prolonged maximum positive and maximum negative values with a sudden drop through the neutral point therebetween. 60 65 70 75

In testimony whereof, I sign this specification.

JULIUS R. BRUECKNER.
